UNITED STATES PATENT OFFICE.

HARRY O. DORSEY, OF CHARLOTTE, NORTH CAROLINA, ASSIGNOR TO WILLIAM C. GUNN, OF FORT SCOTT, KANSAS.

FORCED-DRAFT HOLLOW GRATE-BAR OR BURNER.

1,205,177.

Specification of Letters Patent. Patented Nov. 21, 1916.

Application filed November 27, 1915. Serial No. 63,793.

To all whom it may concern:

Be it known that I, HARRY O. DORSEY, a citizen of the United States, residing at Charlotte, in the county of Mecklenburg and 5 State of North Carolina, have invented new and useful Improvements in Forced-Draft Hollow Grate-Bars or Burners, of which the following is a specification.

This invention relates to certain new and 10 useful improvements in hollow grate bars or burners for closed forced draft furnace beds or floors, and particularly to furnace beds or floors of that type wherein substantially complete combustion of the available heat 15 units of the fuel is designed to be obtained by oxygenation resulting from the upward feed of currents of air through and between the fuel particles from the hollow grate bars, and wherein the clinkers, if any, remaining 20 are raked out through the fuel door and the ashes and other fine refuse discharged through the hollow grate bars into the ash pit.

The primary object of the present invention 25 is to provide hollow grate bars or burners for furnace grates of this character which, are provided with drop bottoms adapted to be freely opened and closed for natural or forced draft and to effect the discharge of the ashes and fine refuse, and 30 which obviates the objections to solid apertured bottoms with sliding or reciprocating closures or other like constructions which are liable to clog or bind or cause other troubles or annoyances.

A further object of the invention is to provide hollow grate bars of the character described composed of lower supporting sections and upper fuel carrying sections which 40 are detachably connected, and which lower supporting sections are provided with means for connection with an air duct for the supply of air under pressure and with hinged drop bottoms of the character described 45 which are adapted to be opened and closed for natural draft or the free and easy discharge of ashes and other fine refuse.

A still further object of the invention is to provide lever mechanism of novel construction for simultaneously and uniformly opening and closing one or more of the drop bottoms of the hollow grate bars in unison, and whereby said drop bottoms may be easily and conveniently operated and main-

tained in open or closed position for any 55 predetermined period.

A still further object of the invention is to provide means for adjusting and regulating the throw of the actuating connections between the dropper bottoms and primary 60 actuating elements so that proper adjustment may be made from time to time to compensate for expansion and contraction, warping or wear of the parts, to insure the proper opening and closing movements of 65 the dropper bottoms.

With these and other objects in view, the invention consists of the features of construction, combination and arrangement of parts hereinafter fully described and 70 claimed, reference being had to the accompanying drawings in which:—

Figure 1 is an irregular vertical longitudinal section through a furnace bed or grate embodying my invention. Fig. 2 is a vertical transverse section on the line 2—2 of Fig. 1. Fig. 3 is a horizontal section through the main elements of the drop door actuating mechanism. Fig. 4 is a detail view of the weighted arm of the actuating shaft 80 and the actuating lever.

The forced draft grate or burner embodying my invention comprises a series of any desired number of hollow grate bars or burners 1, arranged in parallel relation to 85 each other, and each consisting of an upper fuel carrying section 2 and a lower supporting section 3. Each grate bar or burner as thus constructed is in the nature of a substantially oblong rectangular hollow box 90 horizontally and longitudinally divided to form the sections 2 and 3 which may be detachably connected and supported in position in any preferred manner. As shown in the present instance each upper bar or 95 burner section is formed of side walls 4, end walls 5 and a top wall 6, the said top wall being provided with slits or apertures 7 for the upward passage of air to and through the body of fuel, it being understood that the top walls of the hollow bars or burners constituting the grate form the flat floor or fuel carrying surface of the grate which is closed or imperforate, and of a solid type against the downward passage 105 of particles of fuel, with the exception of the slits or apertures 7 for the upward flow of blasts of air. Each lower bar or burner

section is, like the upper section, also in the general form of a trough and comprises side walls 8, end walls 9 and a bottom wall 10. The said lower bar or burner section 5 is open at the top and recessed to receive the base portion of the upper section and open at the bottom, and at intervals the interior of said lower bar or burner section is preferably provided with transverse 10 segmental bracing ribs 11 to reinforce the same in an effective manner.

Each lower bar or grate section 3 is provided with offstanding lateral projections or shoulders 12 to rest upon suitable supports 15 within the furnace casing, and the bottom opening of the section is normally closed by the wall 10. This wall 10 is hinged to form a drop bottom, and for this purpose is provided at each end in alignment 20 with one of its side edges with trunnions 13 journaled in offset bearing portions 14 of bearing plates 15 disposed beneath flanges 16 adjacent to the opposite ends of the body of said grate section and secured thereto by bolts or other suitable fastenings 17. The drop bottoms 10 are adapted to be opened in a downward direction when it is desired to supply air under natural draft to the bed of fuel or to discharge 30 from the hollow interiors or collecting chambers of the grate bars or burners the ashes and other fine particles which may drop downward thereinto through the air blast apertures 7. By providing drop bottoms of this character, and means for operating the same of the character hereinafter described, the bottom openings of the lower grate bar section may be fully opened for the free and unimpeded upward flow of air 40 and also for the free and unimpeded passage of ashes and other refuse, thus obviating the objections to perforated bottoms with slides for controlling the same which are liable to become clogged in use or bind in 45 operation, with obvious annoyances and objections.

The means for actuating the dropper bottoms of any desired number of the grate or burner sections in series comprises a sliding or reciprocating operating rod or bar 18 which is fitted to slide in supporting brackets 19 secured to and depending from the lower sections of certain of the hollow grate bars or burners and has clamped or otherwise adjustably secured thereto blocks 20 provided with wrist pins 21. The wrist pins of the respective blocks, which are equal in number to the grate bars, are respectively connected by links 22 with ears 23 on the hinged dropper bottoms of the grate bars, whereby on reverse sliding motions of the rod or bar 18 the dropper bottoms 10 will be opened or closed, as indicated in dotted and full lines in Fig. 2. One 65 of the blocks is also provided with a wrist

pin 24 which is connected by a motion transmitting link or lever 25 with a crank arm 26 on an actuating rock shaft 27 extending at right angles to the rod or bar 18. The rod or bar 18 may extend, as shown, transversely beneath the series of hollow grate bars or burners and of the furnace casing, and the actuating rod or shaft 27 may extend longitudinally of the casing and outwardly through the front wall thereof, said 75 shaft 27 being journaled at its forward end in the front wall of the casing and at its inner or rear end in a bearing plate 28 secured to a pair of spaced hanger brackets 29 fastened to the lower section of one of 80 the grates or burners. The construction and arrangement of the parts is thus such that the upper grate sections may be readily and conveniently removed for repairs or other purposes without disturbing the lower 85 grate section, while the latter may be easily and conveniently detached when occasion requires for renewal or other purposes, the upper grate sections being removable without disturbing the lower grate sections or 90 the dropper bottom actuating mechanism. Where a limited number, say up to five or six, grate sections are employed a single set of actuating devices of the character described will be sufficient, but where a greater 95 number of grate bars are used they may be divided in series, of a desired number of grate bars to a series, and each series may be operated by a separate set of actuating devices. The outer end of the actuating 100 shaft 27 is provided with a weighted crank arm 30 formed with a socket to receive an actuating lever 31 whereby the said shaft may be rocked, the weighted arm 30 serving to maintain the shaft in either of its 105 opposite positions beyond center to maintain the dropper bottoms in either opened or closed position, as will be readily understood.

In the operation of the grate it is very 110 desirable to provide some means whereby the throw of the links 22, or pivoted connections between the actuating shaft 18 and the dropper bottoms 10 may be varied from time to time, in order to compensate for 115 variations in the relative positions of the grate bars and working parts due to warping, expansion and contraction, etc., particularly in the use of a new grate and until the elements of the grate have set or finally 120 assumed substantially permanent relative positions. To this end, the blocks 20 are made adjustable upon the actuating shaft 18, so that said blocks may be shifted upon the said shaft as required to vary the angular relationship between the link 22 and dropper bottom 10, and consequently vary 125 the degree of motion or throw of said link to secure opening and closing movements of the dropper bottom. As shown particularly 130

in Fig. 1, each block 20 is split or divided at its lower end through which the shaft 18 extends, thus forming jaws which are connected by a bolt and nut or other suitable means, allowing the edges to be relaxed for slidably adjusting the block on the shaft as required and then clamping or fixing it in adjusted position. By the adjustment of these blocks upon the shaft whenever required it will be evident that the connections may be always maintained in proper order to effect full opening and closing movement of the dropper bottoms, with resultant advantages and an increasing of efficiency of the grate.

It will be evident from the foregoing description that my invention provides a hollow grate bar or burner which is simple of construction, durable and efficient in use, and comparatively inexpensive of production, and a series of which may be employed to form a forced draft hollow grate or burner of the character set forth. It will also be seen that the dropper bottoms of the grates may be freely opened whenever it is desired to furnish a natural draft or discharge ashes and other fine refuse, inclosed whenever it is desired to employ a forced draft, the use of the dropper bottoms and actuating mechanism set forth obviating the obvious objections to perforated bottoms with sliding or other controlling valves which are liable to clog or bind and become inoperative or cause annoyance and inconvenience.

In practice, the hollow grate sections may be provided with air from a pump or blower suitably operated in any preferred manner. In the present instance I have shown the bottom section of each hollow grate or burner provided with a short fixed bottom portion 32 having an opening for communication with an air duct or pipe 33 leading from the source of air supply.

I claim:—

1. A grate of the character described including a series of hollow grate sections, each having a drop bottom, an actuating element extending transversely beneath the series of grate sections, connecting members

equal in number to the grate sections and each mounted for independent adjustments upon said actuating element, and members pivotally coupling the different drop bottoms to the different connecting members, whereby the drop bottoms may be separately opened and closed, and whereby the throw of the connecting members may be independently varied.

2. A grate of the character described including a series of parallel grate sections, each provided with a gravity opening drop bottom, a reciprocating actuating device extending transversely beneath said drop bottoms, connecting members, each adjustably mounted upon said actuating device, and links pivotally coupling the drop bottoms to different connecting members in vertical planes out of alignment with each other so as to normally lie at an oblique angle to the drop bottoms and actuating device in the closed position of said drop bottoms.

3. A grate of the character described comprising a series of parallel grate sections, each provided with a hinged or pivoted gravity-opening drop bottom, an actuating device extending transversely beneath said grate sections, and a pivotal connection between each of said drop bottoms and said actuating device, each connection including adjusting means for independently varying the throw of the pivotal connections.

4. A grate of the character described including a series of parallel grate sections, each provided with a hinged or gravity-opening pivoted drop bottom, a reciprocating actuating rod disposed beneath the grate sections, blocks adjustably mounted upon the rod, and links pivotally coupling the respective drop bottoms separately to the different adjustable blocks, whereby the drop bottoms may be opened and closed in the reciprocating motions of the rod and the throw of the links independently varied.

In testimony whereof I affix my signature in presence of two witnesses.

HARRY O. DORSEY.
